WASHING APPARATUS

Jesse H. Clark, Chicago, Ill., assignor, by mesne assignments, to Edison General Electric Appliance Company, Inc., a corporation of New York

Application April 24, 1934, Serial No. 722,099

11 Claims.

(Cl. 141—9)

This invention relates to washing apparatus, more particularly to apparatus for washing dishes, and it has for its object the provision of improved apparatus of this character.

5 More specifically, this invention relates to dishwashing apparatus wherein a cleansing fluid, such as water, is circulated or hurled through the washing vat by suitable power driven means, such as a motor driven impeller, so as to effect a cleansing action on the dishes supported within the vat.

In one of its aspects, this invention contemplates the provision of improved washing apparatus whereby suitable cleansing steps, such as rinsing and washing operations, can be effected in a simple, reliable and efficient manner.

15 In another of its aspects, this invention contemplates the provision of improved manually operable control means for controlling the apparatus so that it will effect these rinsing and washing actions in a predetermined cycle of operations including, for example, such operations as preliminary rinsing and washing steps, a second washing step and finally a second rinsing step.

20 25 A further aspect of this invention is the provision of improved means for automatically supplying the washing chamber or vat with a predetermined quantity of cleansing water for the washing operations so that the most efficient washing action will be effected.

Still another aspect of the invention is the provision of improved means for indicating to the attendant the particular cleansing step that the apparatus is at the time effecting. Thus, if 30 35 the dishes are being rinsed, the signal device will indicate to the attendant that the apparatus is performing this function. Likewise, if the apparatus is washing the dishes, the signal device will indicate this condition. Moreover, it is contemplated that the signal device will indicate 40 when the machine is draining, when it is being filled and when it is in its "off" or inoperative condition.

In accordance with this invention, the vat for receiving the dishes to be cleansed is provided with water supply and drain conduits, and these conduits are controlled respectively by supply and drain valves. Within the vat is a suitable motor driven impeller arranged to circulate the 45 50 cleansing water admitted to the vat over and about the dishes supported within the vat so as to effect a washing action upon them. Also arranged within the vat is a suitable spray device, preferably of the reaction type, which receives the water supplied to the vat and hurls it in

spray form over the dishes so as to effect a rinsing action of the dishes. Whether or not the dishes are washed by the impeller or rinsed by the spray device depends upon the position of the drain valve. If this valve is in its open position while water is being supplied to the vat through the spray device, the water can flow directly to the drain and the dishes will be rinsed, whereas if the drain valve is closed, the water supplied to the vat will accumulate in its lower portion so that it can be engaged by the impeller for more positive circulation in the vat for the washing action proper.

The fluid supply and drain valves and also the impeller driving motor, are controlled by suitable means so as to effect rinsing and washing actions in a predetermined sequence, or so that either one of these cleansing actions can be effected independently of the other and at the will of the attendant. The control device comprises suitable cams for operating the valves, and also for operating a switch for controlling the operation of the impeller motor. These cams are driven to successive controlling positions by means of a suitable electromagnetic device. This device is controlled by a manually operable control device which is arranged so that successive movements of a control member, such as a push button, effects successive operations of the electromagnetic device to advance the cam shaft to successive controlling positions. Each position of the cam shaft effects a corresponding control of the apparatus. Thus, in one position it causes the apparatus to effect a rinsing action on the dishes, in another to effect a washing action, and in still others to effect draining and filling operations.

The control further comprises suitable means controlling the electromagnetic device so that when the dishwashing machine is being filled, the electromagnetic device will be automatically energized to operate the cams to shut off the water supply when a predetermined quantity of water has been supplied to the vat.

The electromagnetic device driving the cam shaft also controls a suitable signal device which is located in a convenient part of the apparatus, such as at the push button station. Each time the electromagnetic device operates to advance the cam shaft, it also effects an operation of the control device to denote the corresponding controlling position of the cam shaft.

For a more complete understanding of this invention, reference should be had to the accompanying drawings in which Fig. 1 is a perspective

view, partly diagrammatic, illustrating dishwashing apparatus embodying this invention, parts of the apparatus being shown in section and parts broken away so as to illustrate certain details of construction; Fig. 2 is a fragmentary elevation of the dishwashing apparatus of Fig. 1, parts being shown in section and parts broken away so as to illustrate certain details of construction; Fig. 3 is a vertical elevation in section illustrating a manually operable control device used in the dishwashing apparatus of Figs. 1 and 2; Fig. 4 is an elevation partly in section of the control device of Fig. 3, but illustrating certain of the parts in different operative conditions, and having certain parts removed; Fig. 5 is a fragmentary elevation partly in section of the control device of Figs. 3 and 4, but illustrating certain of the parts in still different operative conditions; Fig. 6 is a plan view of the control apparatus of Figs. 3, 4 and 5, parts being shown in section and parts being broken away so as to illustrate certain details of construction; and Fig. 7 is a plan view of the control apparatus of Figs. 3, 4 and 5.

Referring to the drawings, more particularly to Fig. 2, this invention is shown in one form as applied to dishwashing apparatus comprising a casing 10 having a rear wall 11, side walls 12, bottom and front walls (not shown) and a top wall 13. These walls are suitably shaped and joined together to define a substantially rectangular casing, and may be formed of any suitable material, such as steel, preferably enameled.

A suitable vat 14 is supported in an upright position within the casing 10. The vat is formed of any suitable material, such as sheet metal, which, as shown, is shaped to define a relatively deep chamber, rectangular in cross-section. The vat is supported by any suitable means in its upright position within the casing. The supporting means forms no part of the present invention and it is believed to be unnecessary, therefore, to describe it in detail.

A removable cover 15 is provided for the vat 14, this cover, as shown, being provided with suitable hinge means 16 securing it to the upper wall 13 of the casing. The cover is provided with a handle 15a whereby it may be conveniently moved between its open and closed positions.

Preferably, the vat 14 and also the cover 15 will be formed of a suitable rust-resisting steel which will be plated or enameled.

Suitable dish-supporting open-work baskets or racks are removably supported in the lower and upper portions of the vat 14. While any suitable dish and utensil supporting racks may be used, it is preferable to use racks arranged substantially in accordance with those described and claimed in the copending application of Forrest A. Walker, Serial No. 621,042, filed July 6, 1932, now matured into Patent No. 2,035,625, and assigned to the same assignee as this invention. It is believed to be unnecessary to describe these racks in detail in this application because they form no part of the present invention. In brief, however, these racks are of open-work form, the general contour of both racks being rectangular so as to fit within the rectangular vat 14. The lower rack 17 only has been shown, but it will be understood that an open-work rack will be positioned directly above it in superposed relation with it.

Arranged within the lower rack is a tray or basket 18 adapted to receive knives, forks, etc.

The bottom wall of the vat 14 is provided with

a plurality (four) of inclined portions 20, which slope downwardly toward the center of the bottom of the vat and terminate in an opening 21 arranged centrally of the vat.

In the lower portion of the vat 14 directly above the bottom opening 21 is a suitable impeller 22 arranged to rotate on an axis substantially coaxial with the vertical central axis of the vat and with the axis of the opening 21. The impeller 22 is operated by an electric motor 23 mounted below the bottom wall of the vat and having its shaft 23a (Fig. 1) extending through the opening 21 into the vat where it has a driving connection with the impeller.

The motor 23 is supported in the bottom wall 15 of the vat by means of a supporting frame 24. This frame 24 is secured to a flange 25 on the vat, surrounding the opening 21, by means of a plurality of bolts 26 (Fig. 1) which are passed through suitable apertures provided for them in 20 the flange and received in a clamping ring 27 supported on the upper side of the flange 25. The frame 24, as shown, is provided with a depending skirt 28 of relatively large diameter. This skirt serves to secure and support the motor 23. The motor 23 is secured directly to a ring shaped member 30 which in turn is secured to the skirt 28 by means of a plurality of bolts 31. Bosses 31a on member 28 provide sufficient material to receive the ends of bolts 31. Preferably, a resilient ring-shaped member 32 will be interposed between the ring 30 and the skirt 28.

The frame 24, in addition to serving as a support for the impeller driving motor 23 has several additional functions; it serves to convey fresh 35 cleansing water to suitable water distributing and circulating means in the vat 14, and further, serves to conduct the soiled water from the vat to a suitable drain. As shown, the frame is provided with a passageway or conduit 33 which 40 functions to convey fresh cleansing water to the vat and with a drain passageway 34 which functions to drain soiled fluid from the vat.

The drain chamber 34, as shown, has a substantially circular shape and its bottom wall 45 slopes downwardly from the left side to the right side of the chamber, as viewed in Fig. 1, where it terminates at the right side in a discharge port 36. This port 36 communicates with a drain conduit 37.

A suitable valve 38 controls communication between the vat and the discharge chamber 34. This valve is provided with a closure portion, as shown, arranged to rest upon a seat 40 so as to close the vat to the drain, and to be elevated from the seat so as to permit soiled water within the vat to flow to the drain. The valve is further provided with a sleeve 41 extending vertically upwardly from the closure portion of the valve and arranged about the motor shaft 23a 55 in substantially concentric relation with it. The space between the sleeve 41 and the shaft constitutes an over-flow drain passage which, it will be observed, communicates directly with the draining chamber 34.

The valve is operated between its open and closed positions by means of a shaft 42. This shaft is mounted for rotary motion within the frame 24, and, as shown, carries a pair of cranks 43 which engage arms 44 depending from the valve so that when the shaft 42 is rotated in a clockwise direction, as viewed in Fig. 1, it will open the valve, whereas when it is rotated in the opposite direction it will permit the valve to close.

The frame 24 supporting the motor and defin-

ing the fluid supply and drain passageways, together with the arrangement of the drain valve, are arranged in general in accordance with the disclosure in the copending application of Karl K. 5 Huppmann, Serial No. 657,781, filed February 21, 1933 and assigned to the same assignee as this invention.

The fluid supply passageway 33 communicates with an upright conduit 45 within the vat. This 10 conduit, as shown, is connected at its lower end with a vertical passageway 46 within the clamping ring 21. This passageway in turn communicates with the supply passageway 33. The upright conduit 45 is turned inwardly to the central vertical axis of the vat, as shown in Fig. 2, and communicates with an upright conduit 47. This conduit in turn communicates with a suitable reaction spray device 47a. It will be observed, in view of this arrangement, that the 20 fluid supplied to the conduit 33 will flow directly to the reaction spray device 47a from which it issues into the vat. In issuing into the vat, it rotates the spray device at a relatively high speed to circulate the water through the 25 dish-supporting racks so as to effect a rinsing action on the dishes within the vat.

The impeller 22 is provided with blades 22a, as shown, which may have any suitable shape, the important feature being that they be given a 30 shape such that cleansing fluid placed within the vat and allowed to accumulate therein will be thrown upwardly and outwardly through the dish-supporting racks in an efficient manner by the rotary motion of the impeller so as to effect a 35 washing action on the dishes within the racks. The blades 22a of the impeller are mounted upon an apron-like member 22b (Fig. 2) which surrounds the upright sleeve 41 of the drain valve, there being sufficient clearance between 40 these members to prevent any interference by the valve to the rotation of the impeller or by the impeller to the operation of the valve between its open and closed position.

Whether or not the impeller can function to 45 wash the dishes depends upon the position of the drain valve 38. If the drain valve be in its open position while water is being supplied to the vat through the reaction spray device 47a, the water will gravitate to the bottom of the vat 50 and flow directly to the drain 37. On the other hand, if the drain valve be closed while the water is being supplied to the vat, the water which gravitates to the bottom of the vat will accumulate therein in a pool which is engaged by the 55 impeller so as to be circulated upwardly and outwardly with considerable force through the dish-supporting racks. That is, assuming that water is being supplied to the vat, whether or not a washing or a rinsing action is effected depends 60 upon the position of the drain valve.

Water is supplied to the vat from a suitable source of supply 48 through a controlling valve 50 to the passageway 33 by means of a conduit 51. As shown, the valve 50 comprises a closure 65 member 52 which controls communication between the conduit 48 and the conduit 51. The valve 52 cooperates with a seat 53 which divides the valve housing into two chambers 54 and 54a, the former communicating with the fluid supply 48 and the latter with the conduit 51. A piston 55 is connected with the valve to operate it to and from its seat 53. This piston is arranged to reciprocate within a cylinder 56, which, as will be seen in Fig. 1, defines the outer 70 wall of the chamber 54. It will be observed that

the inlet conduit 48 communicates with the valve chamber at a point between the piston 55 and the valve seat. The pressure of the fluid introduced is used to control the piston 55 to operate the valve to and from its seat. This control is effected by means of a pilot valve 57 arranged axially of the piston and valve, and further, arranged to provide communication between the chamber 58 at the right of the piston and the chamber 54a of the valve. The piston 55 is so arranged in its cylinder that fluid may leak from the source 48 past the piston to the chamber 58 to hold the valve 52 closed, and the pilot valve is arranged when opened to release this pressure to the chamber 54a so that the pressure acting on the left-hand side of the piston can force the piston toward the right, thereby opening the valve. 15

It will be observed, in view of the foregoing, that when the pilot valve is moved toward the right to open its port, the chamber on the right side of the piston will be placed in communication with the chamber 54a, whereby the pressure on the right-hand side is relieved. As this pressure is relieved, the pressure acting on the left-hand side of the piston forces the piston to the right, thereby opening the valve 52. If the pilot valve is then allowed to move to its closed position, water will leak past the piston to the right side thereof and build up a pressure which eventually will overcome that acting on the left side of the piston, due to the differences in areas of these two sides, and, as a result, the piston will be moved toward the left to close the valve. The pilot valve 57 is biased to its closed position by means of a compression 30 spring 60, and is moved to its open position by means of a cam 61 which engages a follower 62 secured to the pilot valve, as clearly shown in Fig. 1.

This fluid supply cam 61 also controls the admission of a suitable soap or detergent to the vat. The detergent supply means comprises a suitable container 63 in which the cleansing material will be placed, preferably in liquid form; thus, this liquid detergent may be formed 45 of a solution of any suitable cleansing material in water. The upper end of this cylinder communicates with the washing vat by means of a conduit 64. A predetermined amount of the solution in the cylinder is caused to flow into the vat through the conduit 64 by causing an equal quantity of water to flow into the lower end of the container. This introduction of water to the container forces the solution in the upper portion of the container out into the conduit 50 55 64 and thence to the vat.

Water is supplied to the lower end of the cylinder from the supply source 48 through a conduit 65, which at its lower end communicates with the valve 50 and at its upper end communicates with a conduit 66 (Fig. 2). This latter conduit 66 opens into the lower portion of the vat below a distributing screen 67.

The fluid supply from the conduit 48 to the conduit 65 is controlled by means of a valve 68 which is operated by the cam 61. The valve 68, as shown, is biased to its closed position by means of a spring 68a, and is operated to its open position by means of a pin 70 secured to the cam 61 in such manner that when the latter is rotated in a clockwise direction a predetermined distance, it will engage an abutment 71 on the valve and move the valve to its open position. 70

The cam 61 is mounted upon a cam shaft 72 75

which is operated by suitable control mechanism, as will be pointed out in greater detail hereinafter.

Also mounted upon this shaft 72 is cam 73 arranged to operate the drain valve between its open and closed position. As shown, this cam bears against a follower 73a which is secured to the valve shaft 42.

The shaft 72 is also utilized to control the energization of the impeller driving motor 23. This motor is energized from a suitable source of electrical supply, one side of which is represented by the conductor 74 and the other side by the conductor 75. The motor is connected to this supply source through a suitable controlling switch 76 which, when it is in its closed position, connects the motor directly across the supply source 74, 75. The operation of this switch to its closed position is effected by means of a cam 77 mounted upon the cam shaft 72.

The cam shaft 72 is operated to successive controlling positions by means of an electromagnetic device 78 which is mechanically connected to operate the shaft to successive controlling positions by successive operations of the electromagnetic device. The electromagnetic device is mechanically connected to the shaft 72 by a suitable pawl and ratchet arrangement. As shown (Fig. 1), a ratchet 80 is keyed on the cam shaft. Cooperating with this ratchet is a pawl 81 which is mounted upon an arm 82 mounted upon the shaft 72 but having freedom of rotation thereon. The arm 82 is mechanically connected to the armature of the electromagnetic device 78 by means of a link 83. The arm 82 is biased in a clockwise direction, as viewed in Fig. 1, against a stop 84 by means of a tension spring 85.

It will be observed in view of the foregoing construction that when the electromagnet 78 is energized it will attract its armature and in doing so will rotate the arm 82 and the pawl 81 mounted on it in a counterclockwise direction, thereby moving the ratchet wheel 80 and the attached cam shaft 72 in a counter-clockwise direction through one step of motion. When the electromagnet 78 is deenergized, the tension spring 85 will return the arm 82 to its position against the stop 84.

The electromagnetic device 78 is also energized from the supply source 74, 75. Its energization is controlled by means of a suitable switch 86. The operation of this switch is controlled by means of a control device 87. This control device, as shown, comprises a manually operable push button 88 which controls a plunger 90 so that when it is depressed it will effect the closure of the switch 86 to energize the electromagnet 78. The switch is moved directly to its closed position by means of a latching member 81, shown more clearly in Figs. 3, 4 and 5.

The switch 86 comprises a fixed contact 86a mounted within the housing 92 of the control device 87. Cooperating with this contact is a movable contact 86b which is formed of a resilient electrically conducting material arranged so that the contact 86b is biased to its open position by the inherent resiliency of the arm. The latch 91 is also mounted within the housing 92 on a suitable standard 93. As shown, the latch 91 has a pin and slot connection 94 with this standard so that the latch can be moved in a vertical direction relative to the standard to a limited extent. The latch 91 is biased in a counter-clockwise direction, as viewed in Figs. 3, 4 and 5, by means of a compression spring 95.

The plunger 90, operated by the push button 88, is arranged to engage a cam surface 91a on the latch so that when the push button is depressed from its position shown in Fig. 3 to its position shown in Fig. 4, it will not only depress the latch 91, but also will move it in a counter-clockwise direction to its position shown in Fig. 4. When the latch is thus moved to its position shown in Fig. 4, it will engage an abutment 96 carried by the movable contact 86b, as clearly shown in this figure. When the push button 88 is then released the spring 95 will force the latch upwardly and in a counter-clockwise direction so as to close the switch 86 and so as to return the plunger 90 and the push button 88 to their positions shown in Fig. 3.

In view of the foregoing operation, it will be observed that when the push button 88 is depressed and released it will effect the closure of the switch 86 which operation in turn will effect the energization of the electromagnetic device 78 to advance the cam shaft 72 to a successive controlling position.

The latch 91 is released so as to permit the switch 86 to open by means of an electromagnetic device 97 arranged at the control station 87 and in the housing 92, as clearly shown in Figs. 3, 4 and 5. This electromagnet is provided with an armature 98 normally supported in an extended position, as shown in Fig. 1 and in dotted lines in Figs. 3, 4 and 5, by means of a compression spring 100. The armature 98 carries on its lower end a pin 101. This pin 101 is arranged to engage a cam surface 91b on the latch member 91 when the electromagnet 97 is energized to attract its armature 98 so as to move the latch in a clockwise direction, as viewed in Figs. 3, 4 and 5, to thereby effect the release of the switch arm 86b.

The electromagnet 97 is also energized from the electrical supply source 74, 75 and its energization is controlled by means of a switch 102. The switch 102 is operated by means of a cam 103, which in turn is operated by means of the electromagnetic device 78. As shown, the cam 103 is mounted for free rotation upon the shaft 72 and is rigidly connected with the arm 82 so that every time the arm 82 is rotated by the electromagnet to advance the cam shaft through one step, the cam 103 will be operated to close the switch 102. Thus, every time the electromagnet 78 is energized by the closure of the switch 86 to advance the cam shaft, when the shaft 72 approaches the end of its step of motion, the cam 103 will move the switch 102 to close, whereby the energization of the electromagnet 97 will be effected; this device thereupon will operate to effect the release of the switch 86 to permit it to open. This release, of course, permits the spring 85 of the electromagnet 78 to retract the arm 82 to its position shown in Fig. 1. This moves the cam 103 so as to open the switch 102. The foregoing operation conditions the switch 86 for a subsequent operation by the push button 88.

As pointed out in a previous portion of this specification, suitable means are provided for automatically controlling the supply of water to the vat so as to measure a predetermined quantity. This means comprises suitable means for automatically controlling the operation of the electromagnet 78 under certain conditions of operation. This automatic means is controlled in accordance with the load imposed upon the impeller driving motor 23.

This automatic means includes an electromag-

netic device 105 arranged to control a switch 106. The switch 106, together with a second switch 107, effects the automatic control of the electromagnetic device 78. The switch 107 is controlled by means of a cam 108 which is mounted upon the cam shaft 72 and hence is controlled by means of the electromagnet 78. The switch 106 is also controlled by means of a cam 110 which is mounted upon the shaft 72.

10 The function of the switch 107 is to connect the armature circuit of the motor 23 to the electrical supply source 74, 75 through the operating coil of the electromagnet 105 so that the energization of this coil is substantially proportional to the magnitude of the armature current of the motor 23, and the function of the switch 106 acting with the switch 107 is to energize the electromagnet 78 at the proper time.

15 The electromagnetic device 105 functions to latch the switch 106 in its open position after it has been moved to this position by the cam 110. This is accomplished by means of a pivotally mounted latch 111 spring biased to engage the detent 112 on the switch arm so as to hold it in 20 its open position.

20 Under certain conditions of operation, as will be pointed out hereinafter, the switch 107 is closed by the operation of the electromagnet 78 to connect the motor in the supply source through 25 the operating coil of the electromagnet 105 which when the armature current attains a predetermined magnitude attracts the latch 111 to release the switch 106 which thereupon closes. When the switch 106 closes it effects the energization 30 of the electromagnet 78 through the switch 107, which will be closed at this time, to effect an automatic operation of the cam shaft 72 to close the inlet valve 52. In other words, when the 35 load upon the motor 23, that is when a predetermined quantity of water has been supplied to the vat, the electromagnet 78 is automatically controlled to shut off the supply of water.

40 Suitable signal means are provided for indicating to the attendant the condition of operation of the apparatus. In other words, suitable means are provided for denoting to the attendant what condition the control device is in and what the corresponding controlling action of the washing apparatus is. This signal device comprises an 45 indicating dial 114 located at the control station, preferably within the housing 92, as shown in Fig. 3. This dial is provided with a number of indications representing a number of controlling positions of the cam shaft 72. In the particular 50 apparatus shown, the cam shaft has nine controlling positions, and the dial will have numbers 1 to 8 inclusive, and also a zero position indicating the "Off" position. As shown more particularly in Fig. 7, the numerals 0 to 8 are supplemented by other indications denoting the operative 55 conditions of the control, as there indicated, the dial is provided with the word "Off" corresponding to the zero position, the word "Rinse" corresponding to the position 1, the word "Fill" 60 to the position 2, the word "Wash" to the position 3, the word "Drain" to the position 4, the word "Fill" to the position 5, the word "Wash" to the position 6, the word "Drain" to the position 7 and the word "Rinse" to the position 8. It is to be understood that in any case the indicating dial will be appropriately marked so as to denote which of any of the controlling positions 65 that the shaft 72 might be in.

The dial 114 is advanced one step each time the push button 88 is depressed. This is accom-

plished by means of a pawl and ratchet drive operated by the electromagnet 97. As shown (Figs. 1 and 6), this drive comprises a ratchet 115 secured to the dial 114, and a pawl 116 cooperating with the ratchet. The pawl 116 is mounted upon a pivotally mounted lever or arm 117, shown more particularly in Figs. 1 and 6. The lever 117 is operated by means of a drum 118 which is arranged to rotate on the axis of the plunger 90. As shown, the drum 118 is provided with an upright pin 120 which is received in a slot 121 provided for it in the arm 117 so that when the drum is rotated the arm 117 will be rotated with it.

10 The drum 118 in turn is driven by means of the plunger or armature 98 which at its upper 15 end carries a laterally projecting pin 122 which moves vertically within a slot 123 provided in a stationary cylinder 124 surrounding the plunger 98. The cylinder 118 is provided with a slot 125 inclined in such a direction and at such an angle 20 that when the plunger 98 is attracted by the electromagnet 97 it will rotate the cylinder 118, and hence, the arm 117 in a clockwise direction to advance the indicating dial 114 in a corresponding direction through one step of its motion. The ratchet and the dial are prevented 25 from over-traveling by means of an abutment or projection 126 on the arm 117 which at the end of the stroke of the arm to advance the dial moves in front of a tooth in the ratchet 115 to prevent 30 further rotation of the ratchet. A spring 126a bears against the ratchet to prevent movement 35 of the ratchet and dial during the return movement of the arm 117. The plunger 98 is extended by means of the spring 100 which will 40 return the cylinder 118, the arm 117 and the pawl 116 to their positions shown in Figs. 1 and 6 for a subsequent operation of the dial.

45 Preferably, the dial 114 will be covered by a glass member 127. The dial 114 will preferably be made of a suitable translucent material, and under the dial will be placed a suitable source of light which will be energized whenever the control member is moved from its "off" position so as to give a visual indication when the apparatus is operating. As shown, in Figs. 1 and 3, the 50 source of light comprises a suitable incandescent lamp 128 which is mounted within a casing 129 attached to the casing 92. A window 130 is provided between the two casings so that light rays can pass directly from the lamp to the casing 92 55 under the dial 114. The lamp is energized from the source 74 and 75 and its energization is controlled by means of a switch 131 which in turn is controlled by means of a cam 132 mounted upon the cam shaft 72. This cam is arranged to hold 60 the switch closed whenever the shaft 72 has been moved from its position corresponding to the "off" position of the control.

65 It will be understood that all of the switches 76, 102, 106, 107 and 131 are biased to their open positions by any suitable means, such as the inherent resiliency of the movable contact member. In other words, when the movable contact members of these switches are released by their respective cams, the switches will be moved to 70 their open positions.

75 In the operation of the dishwashing apparatus, it will be understood that the dishes and other utensils to be cleansed will be placed in their respective supporting trays within the vat. After the dishes have been placed within it, the cover 15 will be closed and the apparatus is then in condition for cleansing the dishes.

Under the initial condition, when the indi- 75

cating dial is in its "off" position, the controlling cams will be in such position that the fluid inlet valve 52 will be closed, the detergent valve 68 will be closed, the drain valve 38 will be opened, the impeller motor 23 will be deenergized and so will the lamp 128. The controlling cams and their associated controlled members are shown in their "off" positions in Figs. 1 and 2.

In order to start the cleansing cycle, the push button 88 will be depressed, which operation, as previously pointed out, effects the closure of the switch 86 and the locking thereof by the latch 91. When this switch is closed, it completes an energizing circuit for the electromagnetic device 18 from the supply conductor 74 through the switch 86, a conductor 135, and thence through the coil of the electromagnetic device 18 and a conductor 136 to the other supply conductor 75. This energizes the electromagnetic device 18 to advance the cam shaft 72 to its first controlling position, namely, the first "rinse" position.

The cams are so arranged that in this position of the cam shaft, the cam 61 operates the fluid inlet valve to its open position so as to allow water to flow from the conduit 48 into the vat through the reaction spray device 47a; the cam 71 closes the switch 76 so as to complete an energizing circuit for the motor 23 from the conductor 74 through the switch 76, a conductor 136a, a conductor 136b, the armature circuit of the motor and thence to the supply conductor 75 through the conductor 136; and the cam 132 operates the switch 131 to complete an energizing circuit for the lamp 128 from the supply conductor 74, through the switch 131, a conductor 136c and thence through the lamp to the supply conductor 75. This circuit is completed by the cam 132 until the controlling apparatus is returned to its "off" position.

As previously pointed out, at the end of the rotation of the shaft 72 by the electromagnet 78, the cam 103 will be operated to momentarily close the switch 102 which temporarily completes an energizing circuit for the electromagnetic device 97 from the supply conductor 75, the conductor 136, a conductor 137 and thence through the switch 102 and a conductor 138 to the coil of the electromagnetic device 97 and from there to the supply conductor 74. This operation, as has been pointed out in detail, effects the release of the latch 91 to permit the switch 86 to move to its open position, thereby deenergizing the electromagnet 78. This magnet, therefore, is returned to its position shown in Fig. 1 by the spring 85. This operation of the electromagnet 97 also advances the indicating dial 114 to denote the corresponding controlling position of the apparatus, namely the first "rinse" position.

Under these conditions, water will flow into the vat from the supply source 48 through the reaction spray device 47a so as to effect a rinsing action on the dishes and utensils within the vat. This operation will continue until the control is moved from the "rinse" position.

To effect the washing operation proper, the push button 88 is again depressed and again the electromagnetic device 18 will advance the shaft 72 to another controlling position. This is "fill" position of the apparatus. This operation of the cam shaft 72 will have moved the cams to such positions that the inlet valve 52 will be held in its open position, the drain valve 38 will have been operated to its closed position and the detergent valve 68 will have been opened by the pin 75 to permit water to flow from the supply source

through the conduit 65 to the bottom of the detergent chamber 63; this operation, as has been pointed out previously, will cause detergent in the upper portion of the cylinder to flow into the vat through the conduit 64. And the switch 102 will have been closed momentarily to energize the electromagnet 97 to release the switch 86 and to advance the indicating dial 114 to denote the "fill" position of the apparatus. The motor 23 in this position of the shaft 72, rather than being energized through the switch 76, will be connected to the supply source 74, 75 through the operating coil of the electromagnetic device 105 by means of the switch 107. In other words, in this position of the shaft the switch 76 will be opened and the switch 107 will be closed. This energizing circuit may be traced from the supply conductor 74, through the switch 107, through the operating coil of the electromagnetic device 105, thence through the conductor 136b to the armature circuit of the motor 23, and then through the conductor 136 to the supply conductor 75.

Under these conditions, water will flow into the vat from the supply source 48 through the reaction spray device 47a. The water, however, instead of flowing directly to the drain 37 will accumulate in the bottom of the vat because the drain valve 38 is closed. As the quantity of water supplied to the vat increases, the load imposed upon the impeller 22 gradually increases. This imposes an increasing load upon the motor and as a result, the armature current of the motor 23 gradually increases. When the quantity of water accumulated in the vat reaches a predetermined maximum value, the armature current will have become sufficiently large to cause the electromagnet 105 to attract the latch 111 and thereby release the switch 106. This switch thereupon closes and completes an energizing circuit for the electromagnetic device 18; this circuit may be traced from the supply conductor 74, through the closed switch 107, a conductor 140, the closed switch 106, thence by means of the conductor 135 to the energizing coil of the electromagnet 18 and thence through the conductor 136 to the supply conductor 75. This operation causes the electromagnet 18 to advance the cam shaft 72 to another controlling position of the shaft, namely, the "wash" position.

By this operation of the cam shaft 72, the cams will have been moved to such positions that the inlet valve 52 will be closed, the detergent valve 68 will be closed and so will the drain valve 38. The cam 71 will have closed the switch 76 so as to connect the armature circuit of the motor 23 directly to the supply source 74, 75, while the cam 108 will have allowed its switch 107 to open, thereby cutting the coil of the electromagnet 105 out of the motor circuit. The cam 110 will have operated the switch 106 to its open position in which position it will be latched by the latching member 111. The switch 102 again will have been temporarily closed so as to advance the indicating dial 114 to indicate "wash". Under these conditions, no more water will flow into the vat, but that which has been supplied will be retained therein by the drain valve, and the motor will operate continuously to drive the impeller to circulate the water upwardly and outwardly in the vat to effect a thorough washing action on the dishes in the vat. As long as the control apparatus is allowed to remain in this condition the washing action will continue.

When it is desired to discontinue the washing action, the button 88 will again be depressed

which operation will cause the electromagnet 78 to advance the shaft 72 to another controlling position—the "drain" position—and at the same time by the operation of the switch 102 will advance the dial 114 to its "drain" indicating position. During this operation of the cam shaft, the inlet and detergent valves will remain closed and the motor circuit will still be completed through the switch 16. However, the drain valve 38 will be moved by its cam 18 to its open position to allow the soiled water to drain from the vat. The apparatus is now ready for the second washing operation. This is accomplished by depression of the button 88 which advances the cam shaft to the second "fill" position, which at the same time advances the dial 114 to denote second "fill". This effects an operation which is a repetition of the preceding "fill" operation of the control, with the exception that in this case the detergent valve 68 is not opened. That is, water flows into the vat from the supply source 48 and is allowed to accumulate therein because the drain valve will have been closed. The motor circuit, as before, is connected to the supply source 25 through the electromagnet 105 which functions when the motor load increases to a predetermined value to energize the electromagnet 78 to advance the cam shaft to the second "wash" position, in which position the fluid supply valve 52 is closed, and the motor is connected directly to the supply source instead of through the coil 105. The indicating dial will be driven to the second "wash" position when the shaft 72 is driven to close the inlet valve. The second wash will continue until the button 88 is again depressed to effect the second draining of the vat. This operation will move the cams to control their associated devices in exactly the same way as they do in the first "drain" position, except that in this case the cam 40 77 will have allowed its switch 76 to open, thereby deenergizing the impeller motor 23.

The apparatus is now in condition for the second or final rinse, which action is effected by depressing the button 88 to advance the cam shaft to its eighth controlling position, i. e., the final "rinse". This operation of the shaft 72 causes the dial 114 to indicate final "rinse", and the cams to control their associated members as in its first "rinse" position, except that the motor will be deenergized in this latter position. Thus, the inlet valve 52 will be opened to allow water to flow into the vat through the reaction spray device 47a while the drain valve 38 will be opened to allow the water which gravitates to the bottom of the vat to flow directly to the drain. The motor switches 106 and 107 will be opened and so will the motor switch 76. The rinsing action will continue until the button 88 is again depressed to move the cam shaft 72 to the "off" position. In this position of the cam shaft, the switches 76, 106, 107 and 131 will all be allowed to move to their open positions; the drain valve 38 will be held in its open position; and the fluid inlet and detergent valves 52 and 68 will be closed. The operation of the shaft 72 to its off position will cause the dial 114 to advance to denote the "off" position. This completes the cycle of operation.

It is to be understood that it is not necessary to go completely through the washing cycle just described and that any one of the cleansing steps desired can be selected at the will of the attendant merely by depressing the button 88 successively until the control advances to the posi-

tion desired. Thus, suppose it is desired to effect merely the first "rinse" and the second "wash" step, eliminating the first "fill" and "wash" operations. After the first rinsing operation has been completed, the operator will depress the button 88 successively to advance the shaft through the first "fill" position, the first "wash" position and the first "drain" position to the second "fill" position, after which the machine will automatically advance to the second "wash" position and effect a washing action. Again, if it is desired merely to effect a rinsing action, such as on glassware, the attendant can effect the first "rinse" and then depress the button seven times to return the control to the "off" position without effecting any of the intermediate controlling steps of the washing cycle.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. In washing apparatus provided with a vat, in combination liquid supply and drain valves for said vat, power-operated means for circulating liquid in said vat, control means for said valves comprising a control member arranged when moved to a first selected position to open said supply valve and to close said drain valve so that liquid supplied to the vat is retained therein for circulation by said power-operated means and when moved to a second selected position to close said liquid supply valve while permitting said drain valve to remain closed, a manually-operable controlling member for said control member having an inactive position and an active position into which it is manually movable and in which it effects the operation of said control member to said first selected position, and means controlling said control member operably associated with said liquid circulating means to respond to a condition of operation thereof that varies as the quantity of liquid in said vat varies and with said control member to automatically move it to said second selected position when a predetermined quantity of liquid has been supplied to said vat.

2. In washing apparatus provided with a vat, a liquid supply conduit communicating with the vat, a valve controlling the conduit, a liquid circulating impeller in the vat and a motor for driving the impeller, control means for said apparatus comprising a control member movable between a plurality of controlling positions in certain of which said valve is opened and in others of which said valve is closed, manually operated control means for moving said control member to selected controlling positions to open and close said valve, and auxiliary means for automatically operating said control member from a predetermined one of said positions in which said valve is opened responsively to the load imposed on said motor so as to close said valve when the load, increasing because of the increasing amount of liquid in said vat, attains a predetermined magnitude corresponding to a predetermined amount of liquid in said vat.

3. In dishwashing apparatus provided with a vat, a pair of valves to control the supply of cleaning liquid to the vat and the drainage of liquid from the vat, liquid circulating means in

the vat, a motor to drive the circulating means, control means for said apparatus comprising a control member for said valves arranged in one position to open the supply valve and close the drainage valve, and in a second position to close the supply valve while the drainage valve remains closed, control means for said control member including a member by the manual operation of which said control member is moved to said one position and means responsive to the load on said motor to move said control member automatically to said second position to close the supply valve and stop the supply of liquid to the vat when the load on the motor, increasing because of the increasing amount of liquid in the vat, reaches a predetermined magnitude corresponding to a predetermined amount of liquid in the vat.

4. In dishwashing apparatus provided with a vat, a valve to control the supply of cleaning liquid to the vat, liquid circulating means in the vat, a motor to drive the circulating means, control means for said apparatus comprising a cam arranged to control the valve so that in one position of the cam the valve is open and in a second position the valve is closed, and control means for the cam, the control means including a member by the manual operation of which the cam can be moved to its first position in which the valve is open to supply liquid to the vat, and means responsive to the load on the motor to move the cam to its second position to close the valve and stop the supply of liquid to the vat when the load on the motor, increasing because of the increasing amount of liquid in the vat, reaches a predetermined magnitude corresponding to a predetermined amount of liquid in the vat.

5. In dishwashing apparatus having a vat, means for supplying liquid to the vat, a valve controlling the liquid supply means, liquid circulating means in the vat and a driving motor for the liquid circulating means, control means for said apparatus comprising electroresponsive means controlling the operation of said valve to its open and closed positions, an electromagnetically operated switch connected to said electroresponsive means having an inactive position, and an active position wherein it controls the energization of said electroresponsive means to effect an operation of said valve, a manually operable control member for moving said switch to said active position, means controlling the energization of said electromagnetic switch to move it to said inactive position responsive to the operation of said electroresponsive means to effect a control of said valve, and means controlled by said electroresponsive means controlling the energization thereof responsive to the load imposed upon said motor when said motor is operated and said supply valve is opened, due to a predetermined operation of said electroresponsive means, to effect the closure of said supply valve when said load, increasing because of the increase in the amount of liquid in said vat, attains a predetermined magnitude corresponding to a predetermined amount of liquid in said vat.

6. In dishwashing apparatus having a vat, a liquid circulating impeller in the vat, means for supplying liquid to the vat, a valve controlling the liquid supply means, control means for said apparatus comprising a cam controlling the operation of said valve, an electromagnetic device for operating said cam, manually operable switching means controlling the energization of

said electromagnetic device to operate said cam to successive controlling positions, an electromagnetically operated switch controlling the energization of said electromagnetic device having an open position, and a closed position wherein said electromagnetic device is energized to advance said cam to a controlling position, means operated by said electromagnetic device, when operated by said manually operable switching means to move said cam to a selected controlling position, for operating said switch to its open position, and means controlling the energization of said electromagnetically operated switch to move it to its closed position responsive to the armature current of said motor when said valve is open, so as to effect the operation of said electromagnetic device to move said cam to shut said valve when said armature current, increasing because of the increasing amount of liquid in said vat, attains a predetermined magnitude corresponding to a predetermined quantity of liquid in said vat.

7. In dishwashing apparatus having a vat, a valve controlling the supply of liquid to the vat, a liquid circulating impeller in the vat and a driving motor for the impeller, a control system for said apparatus comprising cams controlling the operation of said valve and motor respectively, a cam shaft for operating said cams so that in one controlling position of said shaft said motor is operating and said valve is opened to supply liquid to said vat, and in another controlling position said valve is shut while said motor is operating, an electromagnetic device connected to operate said shaft to successive controlling positions by successive operations of said electromagnetic device, a manually operable control device controlling the energization of said electromagnetic device to operate it successively, a second electromagnetic device controlling the energization of said first electromagnetic device having an active condition wherein when it is energized it effects the operation of said first electromagnetic device to operate said shaft to a succeeding controlling position, and an inactive condition, cam means on said shaft controlling said second electromagnetic device when said shaft is operated to a predetermined controlling position by operation of said manually operable control member so as to effect said inactive condition and so as to effect said active condition when said shaft is moved to said one controlling position by said manually operable control device wherein said motor is operating and said valve is opened to supply liquid to said vat, and means controlling the energization of said second electromagnetic device when in said active condition responsive to the magnitude of said armature current of said motor so as to effect the operation of said first electromagnetic device to move said shaft to said other controlling positions to shut off the supply of liquid to said vat when said armature current, increasing because of the increasing amount of liquid in said vat, attains a predetermined magnitude corresponding to a predetermined amount of liquid in said vat.

8. In dishwashing apparatus having a vat, means for supplying liquid to the vat, a valve controlling the liquid supply means, a liquid circulating impeller in the vat, and a driving motor for said impeller, control means for said apparatus comprising a switch arranged to connect said motor to a source of electrical supply, cams controlling the operation of said valve and said switch

- in a predetermined cycle of operation, an electromagnetic device controlling the operation of said cams, a manually operable control device controlling the energization of said electromagnetic device to operate said cams, a second switch arranged to control said electromagnetic device to move said cams to a controlling position having an inactive position and an active position wherein in said electromagnetic device is controlled to advance said shaft, a cam controlled by said electromagnetic device for moving said second switch to said inactive position, a second electromagnetic device arranged to effect the operation of said switch to said active position to effect the control 5 of said first electromagnetic device, a third switch arranged to connect the operating coil of said second electromagnetic device in the armature circuit of said motor so that its energization is substantially proportional to the magnitude of 10 the armature current of said motor, and a cam operated by said first electromagnetic device for operating said third switch to connect said coil in said armature circuit of said motor.
9. In dishwashing apparatus having a vat 15 means for supplying liquid to and draining liquid from the vat, valves controlling the liquid supply and draining means respectively, a liquid circulating impeller in the vat, and a driving motor for said impeller, a control system for said apparatus comprising a source of electrical supply for said motor, a switch arranged to connect said motor to said source of supply, cams controlling said valves and said switch respectively, a cam shaft for said cams arranged when operated to successive controlling positions to cause said cams to operate said valve and switch in a predetermined cycle of operation, an electromagnetic device mechanically connected to said shaft to operate it to successive controlling positions by successive operations of said electromagnetic device, a manually operable switch controlling the energization of said electromagnetic device to effect the operation of said shaft to its successive controlling positions, a second switch controlling the energization of said electromagnetic device having an open position and a closed position wherein it effects the energization of said electromagnetic device, a cam on said shaft controlling said second switch to move it to its open position, a second electromagnetic device controlling said second switch arranged when energized to effect the operation thereof to said closed position to control said first electromagnetic device, a third switch controlling the energization of said second 20 25 30 35 40 45 50
- electromagnetic device arranged in one position of said shaft to connect said motor to said supply source through the operating coil of said second electromagnetic device whereby said coil is energized in accordance with the armature current of said motor to effect the operation of said first electromagnetic device to operate said cam shaft to shut the liquid supply valve when the armature current of said motor attains a predetermined magnitude, said cams being arranged on 10 said shaft so that in a certain predetermined position of said shaft said liquid supply and drain valves are opened simultaneously whereby liquid is supplied continuously to said vat and drained continuously therefrom.
10. In dishwashing apparatus provided with a vat, a valve to control the supply of cleaning liquid to the vat, liquid circulating means in the vat, and a motor to drive the circulating means, control means for said apparatus comprising a control shaft for said valve arranged in one position to open the valve and in a second position to close the valve, control means for said shaft including a member by the manual operation of which said shaft is moved to said one position to open said valve to supply liquid to said vat, and means responsive to the load on said motor to move said control shaft automatically to said second position to close the valve and stop the supply of liquid to the vat when the load on the motor, increasing because of the increasing amount of liquid in the vat, reaches a predetermined magnitude corresponding to a predetermined amount of liquid in the vat.
11. In washing apparatus provided with a vat, 35 in combination liquid supply and drain valves for said vat, power-operated means for circulating liquid in said vat, control means for said valves comprising a control member arranged when moved to a first selected position to open 40 said supply valve and to close said drain valve so that liquid supplied to the vat is retained therein for circulation by said power-operated means, and when moved to a second selected position to close said liquid supply valve while permitting said 45 drain valve to remain closed, means controlling said control member operably associated with said liquid circulating means to respond to a condition of operation thereof that varies as the quantity of liquid in said vat varies and with said control member to automatically move it to said second selected position when a predetermined quantity of liquid has been supplied to said vat.

JESSE H. CLARK.
